METHOD AND APPARATUS FOR TREATING
HYDROCARBON OILSRobert E. Barry, Washington, D. C., assignor of
one-half to Ralph T. Bassett, Washington,
D. C.

Application April 3, 1928, Serial No. 267,046

2 Claims. (Cl. 196—96)

This invention relates to improvements in method and apparatus for treating hydrocarbon oils, and more particularly to a novel system for use in cracking hydrocarbon oils and purifying 5 the vapors resulting from the cracking operation.

It is well known that unsaturated constituents present after cracking treatment, are in some measure responsible for bad color and odor of the resulting distillates. Prior to this invention, 10 for the purpose of eliminating this objection, the vapors resulting from the cracking treatment have been passed through a suitable catalytic agent, such as fuller's earth, bone black, charcoal, bentonite or the like. It has been found advis- 15 able in such operation, to purify the oil in the vapor phase, and to this end, in one process, the catalytic agent has been maintained in heated condition by means of steam.

The primary object of the present invention is 20 to provide a system in which the use of steam or the like, for heating the catalytic agent, is eliminated, and instead, the vapors from the cracking operation are fed into the catalytic agent in the highly heated condition under which they 25 are discharged from the cracking unit. This heat is then utilized to preheat the oil fed to the cracking unit, whereby heat is conserved.

It will thus be seen that contrary to the usual 30 method of heating the catalytic agent by some extraneous means, I utilize the heat of the cracked vapors to heat the agent and prevent overheating by use of a cooling agent, which cooling agent is preferably the oil fed to the cracking unit, and in this way, the oil is preheated 35 before reaching the cracking unit.

Another object of the invention is to furnish a 40 system in which the vapors may be fractionally separated before a portion of the same is passed into the catalytic agent, and in such system, I may utilize the heated condensate resulting from the separation to heat the catalytic agent. At the same time, the cold oil going to the heating unit may be utilized to cool the catalytic agent, as well as the upper portion of the separator, and 45 in this way, the cold oil aids in the maintenance of a proper temperature in the purifier, and a proper reflux for the separator; and in addition, the feed stock is thus preheated before going to the cracking unit.

50 Another object is to provide a flexible system in which the vapor may be fractionated before some of the same passes to the purifier, or in which the vapors may be passed directly from the cracking unit to the purifier.

55 In my process, the passage of the materials is

so regulated that the catalytic agent is main- 60 tained at a temperature which will prevent crack- ing within the same, and at the same time pre- vent any substantial condensation within the agent.

With the foregoing objects outlined, and with other objects in view which will appear as the de- 65 scription proceeds, the invention consists in the novel features hereinafter described in detail, illus- trated in the accompanying drawing and more particularly pointed out in the appended claims.

The drawing is a diagrammatic view of the ap- 70 paratus which I have devised to carry out the improved process.

In the drawing, 1 designates a pump which 75 draws the oil to be processed from any suitable source, and forces the same through a pipe line 2, to any suitable heater 3 in which the oil is sub- jected to proper temperature and pressure to pro- 80 duce cracking. The oil passes from the heater 75 into any suitable type of reaction chamber 4, and the vapors and gases resulting from the cracking are preferably passed through pipes 5 and 6, into a purifier 7 containing a mass 8 of any suitable 85 catalytic agent, such as fuller's earth, bentonite or the like. In actual practice, the purifier should be arranged sufficiently close to the re- 90 action chamber, so that the vapors entering the purifier have dropped in temperature only slightly below the temperature at which they leave the re- 95 action chamber, and in this way, the catalytic agent is heated. However, such temperature is too high for efficient purification, so I dissipate a proportion of the heat, so as to maintain the 100 catalytic agent at such a condition that cracking, as well as substantial condensation will be pre- 105 vented during the purification step. The heat dissipated is utilized to preheat the cold oil fed to the heater 3, and to this end, the purifier may be provided with a cooling jacket 9, or the like, 110 into which oil may be fed from a valved pipe 10. This pipe is preferably arranged at the lower end of the purifier, and the oil is discharged from the upper end of the jacket, into a conduit 11, through which it may be introduced into the 100 feed pipe at the point 12. It will be obvious that the temperature of the catalytic agent may be controlled by varying the amount of oil fed in the pipe 10 at a given temperature.

The vapors are discharged from the purifier by 105 way of pipe 13, and are then condensed in the condenser 14.

Any slight condensation which may result from the purification treatment, may be discharged from the purifier through a valved pipe 15, lead- 110

ing to an accumulator 16, from which it may be fed by way of a valved pipe 17, into the feed line 2. Such feed may take place while the pump is running, if an injector is used to lead the oil 5 from pipe 17, into the pipe 2.

Instead of passing the vapors from the reaction chamber, directly to the purifier, they may first be led through any suitable stripping of rectifying tower 18, preferably of the bubble cap plate 10 type. To permit this, a valve 19 in the pipe 5 is closed, and a valve 20 in a pipe 21, opened. The vapors remaining after the separation in the stripping tower are passed by way of valved pipe 22, into the pipe 6, and thence into the purifier 15 where conditions are maintained to keep the material in vapor form without any cracking of the vapors. In this embodiment of the invention, the oil used in the cooling jacket of the purifier, may also be used to cool the top of the stripping tower, 20 and for this purpose, a valve 23 in the line 11, can be closed, and then the oil will flow through the valved pipe 24, coil 25, and valved pipe 26, back into the line 11. In this way, the oil added to the feed pipe 2 will be additionally heated. 25 If the vapors are passed into the stripping tower, it will be obvious that the vapors passed through pipe 22 will be of considerably lower temperature than vapors passed through pipe 5, and consequently, it may be necessary to apply additional heat to the catalytic agent, and for this purpose, I may utilize the hot oil from the bottom of the stripping tower, such oil being circulated through valved pipes 27 and 28, and a coil or the like 29, arranged in the catalytic agent. 30 Hot oil from the tower can also be fed through a valved pipe 30 into an accumulator 31, and from the latter, be discharged through a valved pipe 32 into the feed line 2.

While I have disclosed a flexible system, permitting operation in a number of ways, in the preferred mode of procedure, the vapors are

simply passed from the reaction chamber, through pipes 5 and 6, directly into the purifier, and then the cold oil passing around the latter will cooperate with the hot vapors to maintain such a condition within the catalytic material that there will be no cracking, and very little, if any condensation of the vapors, while they are passing through the purifier. 80

It is of course apparent that various changes may be made in the details disclosed, without departing from the spirit of the invention as expressed in the claims. 85

What I claim and desire to secure by Letters Patent is:

1. An oil treating apparatus, including a cracking unit, a rectifying unit and a purifying unit, means for feeding vapors and gases from the cracking unit into the rectifying unit, means for feeding vapors and gases from the rectifying unit into the purifying unit, a mass of a catalytic adsorbent agent arranged in the purifying unit, means for discharging vapor from the purifying unit and for condensing said vapor, a cooling means for the purifying unit, a cooling means for the rectifying unit, means for feeding a cooling agent from one of said cooling means to the other cooling means, a heating coil in the purifying unit, and means for feeding heated liquid from the rectifying unit through said coil. 90

2. A method of treating hydrocarbon oils, consisting in subjecting the oil to sufficient heat and pressure to crack the same, passing some of the oil through a fractionating step and then while it is still in heated condition resulting from the cracking, passing it in indirect heat interchange 100 through a mass of a catalytic adsorbent agent to heat the latter, and passing some of said oil after the cracking step while in vapor form, directly through said catalytic mass, and condensing the vapor after passing the same through the mass. 105
